(57) **CLAIM**

The ornamental design for an extendable tray, as shown and described.

DESCRIPTION

FIG. 1 is a front, top, left perspective view of an extendable tray, showing the new design;
FIG. 2 is a rear, bottom, right perspective view thereof;
FIG. 3 is a front elevation view thereof;
FIG. 4 is a rear elevation view thereof;
FIG. 5 is a left side view thereof;
FIG. 6 is a right side view thereof;
FIG. 7 is a top plan view thereof;
FIG. 8 is a bottom plan view thereof; and,
FIG. 9 is a front, top, left perspective view thereof, shown inside an unclaimed vehicle.

Contrast in materials is shown by line shading.
The broken lines shown in the drawings illustrate portions of the extendable tray and surrounding vehicle that form no part of the claimed design.
